INTERNAL EXPANDING BRAKE FOR
VEHICLES

John Samuel Irving, Birmingham, England

Application August 24, 1944, Serial No. 550,921
In Great Britain June 12, 1943

9 Claims. (Cl. 188—78)

1

This invention relates to improvements in brakes for vehicles and is particularly concerned with shoe separating or spreading means for brakes of the type in which a pair of opposed shoes mounted within a brake drum are adapted to be urged outwardly into contact with the drum to apply the brake.

According to our invention adjacent ends of the shoe webs or abutment members mounted thereon are staggered and a bell-crank or equivalent lever is adapted to fulcrum on and rock about the end of one shoe web or abutment member. One arm of the lever engages the other shoe web or abutment member while the other is acted on by a force applying means, as for example a cable or rod or a fluid pressure operated piston. Thus when a force is applied to the second arm of the bell-crank lever the force tends to rock the lever about its fulcrum and the fulcrum and the first arm urge the shoe ends outwardly in opposite directions into engagement with the brake drum.

A stop is provided for the shoe ends in the "off" position of the brake to facilitate the centering of the shoe assembly and this stop may be fixed to the back plate or may have a limited floating movement if desired.

To take the component of the force applied to the lever in a direction substantially at right angles to the line of movement of the shoe ends a roller may be mounted on or adjacent to the lever fulcrum, this roller rolling on the back-plate or other fixed surface as the shoes move.

Some practical forms of shoe spreading means in accordance with our invention are illustrated by way of example in the accompanying drawings in which—

Figure 1 is a section in a plane at right angles to the back plate of the brake of one form of shoe-spreading means and the adjacent parts of the shoes and back plate.

Figure 2 is a fragmentary section on a larger scale of the shoe-separating lever and the shoe ends showing the movement of the lever in the application of the brake.

Figure 3 is a plan of an alternative form of shoe-spreading means.

Figure 4 is a section through the mounting for the shoe-spreading means shown in Figure 3.

Figure 5 is an elevation of the shoe-spreading means shown in Figures 3 and 4 and the adjacent parts of the shoes.

Figure 6 is a section taken substantially on the line 6—6 of Figure 3 looking in the direction of

2

the arrows and omitting the ends of the brake shoes.

In Figures 1 and 2, 10, 11 are the webs of a pair of arcuate brake shoes mounted in the ordinary way on a stationary back-plate 12 and adapted to be expanded into contact with a rotating drum to apply the brake. The shoe webs 10, 11 lie in the same plane parallel to the back-plate, and there are riveted or otherwise secured to the adjacent ends of the webs flanged sheet metal pressings 13, 14 which extend towards each other and the free ends of which are oppositely staggered to lie in spaced parallel planes. The extremity of the pressing 14 which lies nearest the back-plate is received in a longitudinal slot in a pivot-pin 15 of which the axis is parallel to the back-plate. This pin forms a fulcrum for a bell-crank lever 16, the lever having an arcuate notch 17 at the junction of its limbs of substantially the same radius as the pin with which it engages. Rotatably mounted on the pin on each side of the lever is a roller 18 adapted to roll on the flat surface of a fitting 19 secured by studs 20 to the back-plate 12 in which a recessed opening is pressed to receive it. Notches are cut in the end of the pressing 14 to clear the rollers.

One arm of the bell crank lever 16 extends away from the back-plate and engages the free end of the pressing 13 on the shoe 10. The other arm extends towards the shoe 10 and normally lies at a small angle to the back-plate as shown in Figure 1. Pivotally connected to the free end of this arm is a fork end 21 to which is connected an actuating cable or rod 22 passing through an opening 23 in the fitting 19 and having its axis at right angles to the back-plate.

A pull applied to the cable or rod 22 draws the second arm of the lever 16 towards the back-plate as indicated by the dotted lines in Figure 2 and rocks the lever about its fulcrum, the pivot pin 15. The first arm of the lever thus urges the shoe 10 outwardly towards the drum and at the same time the reaction on the fulcrum urges the shoe 11 in the opposite direction also into engagement with the drum. The leverage obtained depends on the respective lengths of the arms of the bell-crank lever and can be selected according to requirements. The component of the force applied to the lever which is directed towards the back-plate is taken by the rollers 18 which are free to roll on the fitting 19 so that there is no tendency for the shoes to be distorted or displaced laterally.

55 A stop for the shoes in the "off" position is

formed by a steady post 24 which is secured to the fitting 19 on the inner or outer side of the lever and extends at right angles to the back-plate. This post is notched as shown at 25 on opposite sides to receive laterally extending portions of the ends of the pressings 13, 14, which are urged against the post by the usual pull-off spring or springs when the brake is released so that the shoes are automatically centered.

In the modified arrangement shown in Figures 3 to 6, 30, 31 are the two brake shoes having webs 32, 33 which extend towards each other from the ends of the shoes. The projecting ends of the webs are offset in opposite directions from the central plane of the shoes and their lengths are such that in the "off" position of the shoes their extremities just overlap. Secured to the back-plate midway between the shoe ends is a steady post 34 having opposed notches 35, 36 parallel to the back-plate to receive and form stops for the ends of the shoes. The webs are located in a lateral direction by slitting their ends which are wider than the post 34 and cranking them as shown at 37 in Figure 3 to engage the outer surface of the post. The post 34 is also formed with a longitudinal slot 38 intersecting the notches 35, 36. This slot houses a floating cranked two-armed lever having one limb 39 extending substantially at right angles to the back-plate and engaging the free end of the web 32 in the notch 35. At the junction of the limbs the lever is notched to provide a surface 40 which engages the free end of the web 33 in the notch 36. The other limb 41 of the lever extends substantially parallel to the back-plate, and pivoted to its free end is a fork end 42 to which is connected a tension rod or cable 43. Adjacent the junction of the limbs the lever has a lug 44 which is notched to receive the reduced central part of a roller 45 of bobbin form. The roller is housed in an enlargement of the lower end of the slot 38 in the post and is adapted to roll on the lower surface 46 of the slot as shown more particularly in Figure 5.

When a pull is applied to the rod or cable 43 the lever fulcrums about its engagement with the shoe web 33 and the limb 39 urges the web 32 to the left in Figures 3 and 4 while the reaction on the fulcrum urges the web 33 to the right. The component of the force applied to the lever acting in the direction of the back-plate is taken by the roller 45 rolling on the surface 46.

In the arrangement shown in Figures 1 and 2 the roller is co-axial or substantially so with the point about which the lever rocks, but in the arrangement shown in Figures 3 to 6 the roller is spaced from the fulcrum, and to allow for the angular movement of the lever about its fulcrum when the brake is applied the surface 46 with which the roller engages may be curved.

To allow for the angular movement of the shoes about their pivots in the application of the brake or adjustment of the shoes the lever instead of being arranged to rock about a pin in the shoe end as shown in Figures 1 and 2 may be so mounted that it can rock in two planes at right angles to each other relative to the shoes.

I claim:

1. Shoe separating means for a brake of the type set forth comprising opposed staggered abutments in adjacent shoe ends, a post fixed to the back-plate of the brake and having opposed notches to receive the abutments for which it forms a stop in the "off" position of the shoes, a cranked two-armed lever fulcruming on one of

said abutments, one arm of said lever extending substantially at right angles to the back-plate and engaging the other abutment, the second arm of the lever extending substantially parallel to the back-plate, and means for applying to the second arm a force directed substantially at right angles to the back-plate to rock the lever about its fulcrum.

2. Shoe separating means as claimed in claim 1 in which the lever is housed in a longitudinal slot in the post intersected by the notches in which the staggered abutments are received.

3. Shoe separating means for a brake of the type set forth having a pair of movable brake shoes comprising opposed abutments on adjacent shoe ends, said abutments being offset on opposite sides of the median plane of the shoes and substantially opposite each other, a full-floating cranked two-armed lever in free rocking engagement with both of said abutments, one arm of said lever extending between said abutments and the second arm extending in a direction substantially parallel to the back-plate of the brake and generally in the median plane of the shoes, the engagement of said two-armed lever with said abutments serving to maintain said lever in operating position, and means for applying a force to the second arm to move the lever angularly.

30 4. Shoe separating means for a brake of the type set forth having a pair of movable brake shoes comprising opposed abutments on adjacent shoe ends, said abutments being offset on opposite sides of the median plane of the shoes and substantially opposite each other, a full-floating cranked two-armed lever in free rocking engagement with both of said abutments, one arm of said lever extending in a direction substan-

35 tially at right angles to the back-plate of the brake between said abutments, a pivot-pin mounted on one of said abutments with its axis parallel to the back-plate of the brake, one face of said pin being engaged by the lever, the engagement of said two-armed lever with one of

40 said abutments and with said pivot pin serving to maintain said lever in operating position, a roller mounted on said pin and rolling on the back-plate, a second arm of the lever extending substantially parallel to the back-plate and generally in the median plane of the shoes, and means for applying a force to the second arm of

45 the lever to move the lever angularly.

5. Shoe separating means for a brake of the type set forth comprising opposed staggered abutments on adjacent shoe ends, a post fixed to the back-plate of the brake and having opposed notches to receive the abutments for which it forms a stop in the "off" position of the shoes, a longitudinal slot in the post intersected by said

50 notches, a cranked two-armed lever of which one arm is housed in said slot and extends between the abutments with which it is in free rocking engagement and the other arm extends substantially parallel to the back-plate, and means for applying to said latter arm a force directed substan-

55 tially at right angles to the back-plate to move the lever angularly.

6. Shoe separating means as claimed in claim 5, including a roller mounted on the lever adjacent the junction of the arms, said roller being adapted to roll on a surface at the end of the slot in the post adjacent the back-plate.

60 7. Shoe separating means for a brake of the type set forth having a pair of movable brake shoes, comprising opposed abutments on adjac-

65 ent shoe ends, a post fixed to the back-plate and having opposed notches to receive the abutments for which it forms a stop in the "off" position of the shoes, a cranked two-armed lever fulcruming on one of

cent shoe ends, said abutments being offset on opposite sides of the median plane of the shoes and substantially opposite each other, a full-floating cranked two-armed lever in free rocking engagement with both of said abutments, one arm of said lever extending substantially at right angles to the back-plate of the brake between said abutments and the other arm extending substantially parallel to the back-plate and generally in the median plane of the shoes, the engagement of said two-armed lever with said abutments serving to maintain said lever in operating position, and means for applying a force to the latter arm to rock the lever angularly.

8. Shoe separating means for a brake of the type set forth having a pair of movable brake shoes, comprising opposed abutments on adjacent shoe ends, said abutments being offset on opposite sides of the median plane of the shoes and substantially opposite each other, a full-floating cranked two-armed lever in free rocking engagement with both of said abutments, one arm of said lever extending substantially at right angles to the back-plate of the brake between said abutments and the other arm extending substantially parallel to the back-plate and generally in the median plane of the shoes, the engagement of said two-armed lever with said abutments serving to maintain said lever in operating position, means for applying a force to the latter arm to rock the lever angularly, and means for taking the component of the force applied to the lever in a direction substantially at right angles to the back-plate.

9. Shoe separating means for brakes of the type set forth having a pair of movable brake shoes, comprising opposed abutments on adjacent shoe ends, said abutments being offset on opposite sides of the median plane of the shoes and substantially opposite each other, a full-floating cranked two-armed lever in full rocking engagement with both of said abutments, one arm of said lever extending substantially at right angles to the back-plate of the brake between said abutments, a roller mounted on said lever adjacent the junction of the arms and adapted to roll on the back-plate of the brake, a second arm of the lever extending substantially parallel to the back-plate and generally in the median plane of the shoes, the engagement of said two-armed lever with said abutments serving to maintain said lever in operating position, and means for applying a force to said second arm to rock the lever angularly.
